UNITED STATES PATENT OFFICE.

DARLEY B. DOVEL, OF PICKERINGTON, OHIO.

EXHIBITING OR SIGN-DISPLAY APPARATUS.

1,353,734.

Specification of Letters Patent. Patented Sept. 21, 1920.

Application filed April 3, 1916. Serial No. 88,551.

To all whom it may concern:

Be it known that I, DARLEY B. DOVEL, a citizen of the United States, residing at Pickerington, in the county of Fairfield and State of Ohio, have invented new and useful Improvements in Exhibiting or Sign-Display Apparatus, of which the following is a specification.

This invention relates to an exhibiting or sign display apparatus, designed to be disposed in railroad stations, hotels, store windows and other public places, for the purpose of displaying consecutively and intermittently a continuous series of signs, arranged upon an endless traveling belt and employed in conjunction with illuminating means to give a desired effect.

The object of the invention is to provide an exhibiting or sign displaying apparatus in which the sign displaying mechanism is arranged within a water-proof casing, which may be exposed for out-door display so as to protect all the parts of the sign mechanism in inclement weather, and which is also so constructed as to permit of the ready assemblage, disassemblage, cleaning, repairs and changing of the elements of the contained sign mechanism whenever occasion requires.

A further object of the invention is to provide a sign display mechanism including a moving transparent or translucent web carrying the sign matter and which is positively driven in operation from an electric motor and automatically maintained in a taut condition, and which is periodically moved to bring portions thereof carrying different signs into position before a display opening and maintained for a predetermined period in displaying position.

A still further object of the invention is to provide a sign display apparatus in which the moving web is arranged to form a loop in proximity to the display opening, the stretch of the web which forms the forward member of the loop being spaced sufficiently from the rear member of the loop to provide an illuminating chamber or zone into which light is projected, the arrangement being such as to provide for illumination in different colors so as to produce an ornamental and attractive type of mechanism.

The invention consists of the features of construction, combination and arrangement of parts herein fully described and claimed,

reference being had to the accompanying drawings in which:—

Figure 1 is a front elevation of a sign display apparatus embodying my invention. 60

Fig. 2 is a central vertical front to rear section therethrough.

Fig. 3 is a vertical front to rear section taken on the line 3—3 of Fig. 1.

Fig. 4 is a horizontal transverse section 65 through the display apparatus.

Figs. 5 and 6 are detail views on an enlarged scale of the parts of the motion transmitting mechanism.

Fig. 7 is a diagrammatic view of the circuit arrangement.

Fig. 8 is a detail view showing a feature of construction.

Fig. 9 is a side elevation showing a modified construction of motion transmitting 75 mechanism.

Fig. 10 is an edge view of the same.

Fig. 11 is a view of the opposite side of the cam disk from that shown in Fig. 9.

Fig. 12 is a detail view of the adjustable 80 cam plate.

Referring now more particularly to the drawings, 1 represents an inclosing box or casing, which is made of metal or other light, strong and durable material, and 85 which may be constructed in practice so as to be hung from or secured to any suitable support. In practice, the parts of the casing will be preferably made of flat and angle metal strips and sheet metal plates suitably 90 secured together to provide a water-proof inclosure for the contained working parts. At the front the casing is provided with a hinged door 2, and at the sides or ends with hinged doors 3 and 4, designed to be fastened 95 in closed position by any suitable type of fastening means generally indicated at 5, whereby access may be obtained to the front and sides of the casing for convenience in reaching all of the parts of the display 100 mechanism, so as to adapt the same to be applied, removed, cleaned or repaired with facility. The front door 2 is provided with a display opening 6 of suitable size which is preferably covered with a glass or other 105 suitable transparent protecting panel 7.

The signs or other matter to be displayed are printed or otherwise placed upon a moving endless belt or web 8, which may be made of vellum, celluloid or other preferred 110 transparent or translucent material, and the side edges of this web or strip are suitably

2
 secured to attaching strips 9 carried by endless chains 10 passing at their upper ends around sprocket wheels 11 on a series of upper horizontal transverse supporting and 5 guiding rollers 12, which are provided with gear pinions 13 in mesh with each other, whereby all the rollers of the series are driven at a uniform speed in synchronism to transmit proper motion to the endless web 10 or belt. The rollers 12 are journaled in suitable bearing plates or brackets 14 arranged in the upper portion of the casing 15 adjacent to the sides thereof.

The endless web or belt is arranged in 15 the form of a series of vertical loops 15 which pass at their lower ends over guiding and tension rollers 16, journaled at their ends in guide slots 17 in bracket plates 18 suitably fastened to the casing. Preferably 20 said rollers are journaled in bearing blocks 19 which are vertically movable in the slots and are controlled by tension devices 20, each consisting of a spring 21, a head or plate 22, to which the bearing block and the 25 spring are attached and a screw stem 23 for adjusting the head or plate, whereby the rollers are normally held acted upon by spring pressure to take up any slack which may exist in the web, while at the same time 30 the spring may be tensioned to vary the tension on the web to any degree desired.

The endless web also has a front portion arranged in the form of a loop 24 which is disposed immediately in rear of the panel 35 7 and which is formed by portions of the web passing around upper and lower guide rollers 25 and 26, the stretches of the web forming said loop 24 thus being maintained 40 spread apart to form an intervening light transmitting space 27. The signs are illuminated 45 by means of electric lights 28 which are secured to wooden strips 29 at the sides of the casing adjacent to the front wall thereof, preferably by means of brackets 30 which are fastened to the adjacent corner 45 angles of the casing. The lights 28 are arranged in groups of three, two groups on each wooden strip, the bulbs of each group being preferably of three different colors, and 50 said bulbs being arranged in an electric circuit 31 in such a manner that a bulb of the same color in each group will be simultaneously lighted, and the bulb of the different colors successively lighted in regular 55 or irregular order as desired, the means for opening and closing the circuit comprising a circuit breaker 32 arranged upon a horizontal shaft 53 driven from an electric motor 34, which may be supplied with current 60 from any suitable source. It will thus be evident that the front stretch of the loop 24, which will be constantly changing, but will always present, when the web is at rest, a complete sign or display through the 65 panel 7, will be illuminated by the passage

of the rays of light projected into the light transmitting space by the lamps. Thus the display signs will be positively illuminated so as to be clearly observed at a considerable distance during the day or night, and as the 70 light will be constantly varied in color it will be seen that an ornamental and attractive type of sign display mechanism is produced.

The shaft 33 is adapted to transmit intermittent motion to the supporting and drive rollers 12 through the medium of intervening gearing and clutch mechanism, which gearing comprises a spur gear 35 mounted on a stub shaft 36 journaled on a bracket 80 37 which is suitably secured to the casing. Fixed to this spur gear 35 is a miter or beveled gear 38 which meshes with a similar gear 39 loosely mounted on the shaft 33, the hub 40 of said gear 39 being journaled 85 upon a bracket 41 suitably secured to the bracket 37. This hub 40 is formed with a clutch notch or recess 42 adapted to receive a tooth or projection 43 on the upper end of a sleeve 44. The sleeve 44 is fitted to slide 90 vertically on the shaft 33, but is connected for rotation therewith by means of a pin 45 projecting from the shaft and engaging a slot 46 in the sleeve, the construction being such that when the sleeve is moved upward 95 it will couple the gear 39 to the shaft 33 to revolve therewith, while on the downward movement of the sleeve it will release the gear 39 which will turn idly on said shaft, provision thus being made for transmitting 100 motion to the endless web at proper intervals.

The sleeve 44 is provided with an annular groove 47 to receive projections 48 upon the fork arms of a forked lever 49, which lever 105 is pivotally supported upon a bracket arm 50, and normally held in a depressed condition by a spring 51. The said lever has a depending arm 49' which is adapted to be engaged and elevated once upon each revolution of the 110 shaft 33 by means of a striker or tappet arm 52 on a shaft 53 journaled upon the bracket 50, so that once on each revolution of the shaft 53 the lever 49 will be raised to throw the clutch device into action, the spring 51 115 serving after the passage of the tappet 52 beyond the arm 49' to move the lever back to normal position and throw the clutch devices out of engagement to stop the motion of the web. On the shaft 53 is a worm 120 gear 54 which receives motion from a worm 55 on the shaft 33, whereby the shaft 53 is driven in timed accord with the other parts of the display mechanism.

In Figs. 9 to 12, inclusive, I have shown a 125 modified construction of the intermittent clutch actuating mechanism above described, wherein the depending arm 49^a of the forked bell crank lever 49^b, corresponding to the lever 49, is provided with a friction roller 130

56 to traverse the surface of a heart-shaped cam member 57 and a cam groove 58 formed between one side of said cam member and a cam plate 59, whereby to impart motion 5 to the clutch member 44. The said cam member 57 and cam plate 59 are mounted upon one side of a flat circular disk 60 which is keyed or otherwise fixed to the shaft 53, and the point of the cam member 10 57 is loosely mounted on said shaft for pivotal motion. The construction and arrangement of the cam surfaces is such as to positively rock the lever arm 49^a downwardly and upwardly, once on each revolution 15 of the shaft 33, to positively throw the clutch member 44 into and out of action at and for prescribed periods. Both the cam member and cam plate are adjustable to vary these time periods of action, and to 20 this end the cam member 57 is provided on its side facing the disk with a laterally projecting pin or stud 61 which projects into and through a slot 62 formed in the disk and is engaged at opposite sides by micrometer screws 63 carried by posts or studs 64 25 on the disk. By this construction the cam member may be pivotally adjusted on the shaft 53 as an axis in a forward or rearward direction, considering the direction of rotation of the gear, to advance or retard 30 the clutch shifting action and to give a micrometer adjustment to regulate the movement of the curtain before the glass panel and to space and regulate the time period 35 of operation of the same accordingly. The plate 59 is adjustable to accord with the degree of adjustment of the cam member 57 by means of segmental slots 65 therein receiving clamping screws 66 which pass 40 through said slots and work in threaded openings in the disk, whereby the plate may be adjusted and clamped in adjusted position in an obvious manner.

From the foregoing description, taken in 45 connection with the drawings, the construc-

tion and mode of operation of my improved exhibiting or sign display apparatus will be readily understood, and it will be seen that the invention provides a device of this character which is simple of construction, 50 positive, reliable and efficient in operation, and which may be employed for either internal or external use in public edifices and at public places and provides an alluring and attractive presentation of the sign or 55 other matter by virtue of the varicolored illumination of the acting portions of the web.

I claim:—

A display apparatus comprising a substantially rectangular casing, an upper series of guiding and driving rolls arranged in a common horizontal plane and geared together, a lower series of guiding and tensioning rolls, all arranged normally in a 60 common horizontal plane, spaced parallel plates arranged within the casing adjacent the bottom thereof, each plate having a plurality of parallel slots, blocks slidably fitted in the respective slots, the rollers of the 65 lower series being journaled in said slots, springs arranged in said slots and bearing against the blocks for tensioning the lower series of said rollers, elevating guiding rollers arranged in a higher plane than the 70 rollers of the upper series, an endless belt passing alternately over the upper rollers and under the lower rollers and also passing over said elevated rollers to clear the upper set of guiding rollers, the rollers of the 75 lower series being independently yieldable and means for positively driving all of said upper guiding rollers at the same speed.

In testimony whereof I affix my signature in presence of two witnesses.
